UNITED STATES PATENT OFFICE.

WILLIAM MURRAY MORTON, OF DARVEL, SCOTLAND.

DESIGN FOR CARPET.

40,870.

Specification for Design.

Patented Sept. 6, 1910.

Application filed April 18, 1910. Serial No. 556,269. Term of patent 3½ years.

To all whom it may concern:

Be it known that I, WILLIAM MURRAY MORTON, a subject of the King of Great Britain, and resident of Hastings Square, Darvel, Ayrshire, Scotland, have invented a new, original, and ornamental Design for Carpets, of which the following is a specification, reference being had to the accompanying drawings, forming a part thereof.

The figure is a plan view of a portion of a carpet embodying my new design.

The design comprises a border the main feature of which is branches having roses and rose leaves thereon the branches crossing one another at intervals and forming elliptical shapes in which the roses appear and a plain ground filling.

I claim—

The ornamental design for a carpet, as shown and described.

WILLIAM MURRAY MORTON.
